PERMUTATION LOCK

Filed May 2, 1921

Fig. 2.

Fig. 1.

Fig. 3.

Fig. 4.

Fig. 5.

A technical drawing of a gear assembly. It features a large outer gear with a diameter of 15 and a thickness of 2. Inside it is a smaller gear with a diameter of 37. A central hub has a diameter of 30 and a bore diameter of 31. A pinion gear with a diameter of 15 is mounted on the hub. The assembly is labeled with numbers 15, 2, 37, 30, 31, 65, 66, 64, 34, 32, 46, 67, 60, and 1. The word 'UNLTD' is also present.

UNITED STATES PATENT OFFICE.

FRANK HORAK, OF VALPARAISO, INDIANA, ASSIGNOR OF ONE-HALF TO MAX HIRSCH,
OF VALPARAISO, INDIANA.

PERMUTATION LOCK.

Application filed May 2, 1921. Serial No. 466,289.

To all whom it may concern:

Be it known that I, FRANK HORAK, a citizen of the United States, residing at Valparaiso, in the county of Porter and State 5 of Indiana, have invented certain new and useful Improvements in Permutation Locks, of which the following is a specification.

My invention relates to improvements in permutation locks and it more especially 10 comprises the features pointed out in the annexed claims.

The purpose of my invention is to provide a non-pickable lock in which the key is permanently enclosed in the lock; that can be 15 locked through the pressure of a single button; that is a true permutation lock, the combination of which is only known to the owner; that provides an unlocking member having no notches, grooves or special formations, of any kind whatever, thereon; and that can be applied to automobiles, steering 20 wheels, vaults, door-locks etc., as may be desired.

With these and other purposes in view, I 25 illustrate in the accompanying drawing such instances of adaptation as will disclose the broad underlying features without limiting myself to the specific details shown thereon or described herein.

30 Figure 1 is a longitudinal elevation in section showing the parts still locked, with the key in permissive position and the unlocking member ready to complete the unlocking operation.

35 Fig. 2 is a view similar to Fig. 1 showing the key in its obstructing position, the locking parts locked and the tumblers dispersed.

Fig. 3 is a cross section on line 3—3 of Fig. 1.

40 Fig. 4 is a detachable plan view of the locking part.

Fig. 5 is an elevation in section of the locking parts unlocked.

45 Fig. 6 is a cross sectional elevation of enclosed indicating notches, used as an alternative to the visible graduations of the dial.

50 The exemplification shown in the drawing is suggestive of an application that can be made of the invention, as a safety feature on automobiles to prevent theft, but this special feature of adaptation is subject to modification according to the exigencies of various practical requirements.

55 In its broadest aspect this invention is not limited to the specific embodiment instanced

in the drawing, but may be applied to any purpose to which it can be adapted. For instance the housing or casting 1 may be of any desired form dependent on the special use to which the lock is to be applied. In 60 any suitable housing a cylindrical or other shaped casing 2 is seated, wherein it is held by a hardened pin 3, instead of an easily removable screw. Over such a pin a certification plate 4 may be placed to cover the location of the pin. The pin 3 is placed in position so as to fit tightly and it is then smoothed off flush with the housing 1.

At the outer end of the casing 2 a tumbler manipulating cap 11 is placed, and the inner 70 end of the casing has formed thereon a "pillar" 5 that meets a shoulder which becomes a distancing stop serving to determine the inward position of the casing 2 in the housing 1. A cross bolt 51 constitutes the secondary 75 locking feature. It is actuated at right angles to the casing 2 and is controlled by a push button 58 so as to lock, and by the mechanism within the casing to unlock the primary bolt 61 by the simple pressure of a 80 button 50 on the outside of the cap 11 after the interior mechanism has been placed in a permissive relation through the manipulation of the cap or dial.

The casing 2 has a large chamber 7 which 85 terminates in a shoulder 9, and a shallow recess 6 at the other end. A smaller diameter opening 8 joins the recess 6 and the chamber 7, between the recess shoulder 10 and the chamber shoulder 9. The chamber 7 is 90 closed by the cap 11 that has a tubular extension 15 which surrounds a recess 33 that ends in a shoulder against which the large end 34 of the key spindle abuts. A flange 12 is a part of the cap 11. It contains the 95 graduations 13 by means of which the successive positions of the permutation tumblers are determined when the cap is moved to and fro by the knurled head 14. This cap is held in place by an arc shaped latch 16 100 inserted in a slot of the casing as shown in Figs. 1 and 3. The latch 16 projects through the casing so as to enter the circumferential groove 17 formed in the tubular part 15 of the cap and it thus holds the cap in place in 105 the casing against endwise displacement, but free to be rotated in the chamber 7.

A key notch 19 is formed at the inner end of the part 15, into which a projection 43 of the key 37 may pass to lock the cap during 110

the time the key is in permissive position to admit an unlocking pin 47 to be moved alongside the unnotched edge of the key 37 so as to actuate the primary bolt 61 whenever the thumb button 50 of pin 47 is pressed as far as the flange 49 permits it to move until this flange engages the head 14. The tube-end 15 has a pin 20, which serves to "pick up" the first tumbler 21 during the working of the combination. Flange 12 may be seated in a recess 18 of the housing and a "zero" or starting line may be marked on the housing adjacent the dial 13, in any well known manner.

15 The key-holding spindle has a large diameter end 34, that seats in the recess 33 of the cap; and a small diameter end 30 which rests in the bore 8. At this portion of the spindle, a pin 36 is placed to hold it permanently connected to the casing 2. The spindle has a slight shoulder 31 that forms an abutment, against which the tumbler separating washer 28 is fixed by pressure or otherwise; a second shoulder 32 is formed by the large end 34 of the spindle. On the portion of the spindle between the washer 28 and the shoulder 32, the first tumbler 21 has free movement; and between the washer 28 and the shoulder 9, the second tumbler, 24, also has free movement.

20 A key 37 is permanently enclosed within the lock as shown in Fig. 1. It is a flat key and straight along one edge. On the other edge, there is a notch 39 against which

25 springs 40 abut between the curved front end 38, engaged by the rounded end 48 of the pin 47, and the side projection 43 adapted to enter the notch 19 as the key is pressed sidewise against the pressure of springs 40 whenever the smooth pin 47 is moved past the key. Beyond the projection 43, at 44 within range of the tumblers 21 and 24, the key has no notches whatever until the end is reached. Here a notch 45 is formed

30 leaving a toe 46 at the inner extremity of the key. The key has a radial and slight lengthwise movement in the slot 35 formed from end to end of the spindle. This slot extends radially from a hole formed in the center of the spindle, which is approximately of the same diameter as that of the pin 47, the bottom of the slot being one side of such hole which is permanently aligned with an entrance hole formed through the cap 11. Half round recesses 42 are formed in the side walls of slot 35 for springs 40, and a spring plate 41 is placed between the springs and the inside of the cap 11.

35 Each of the tumblers 21 and 24, and the washer 28, have openings into which the spindle is placed. The first tumbler 21 has a key notch 22 which opens into its central hole, and the second tumbler 24 has a similar notch 27, while the washer 28 also has a key notch 29 that is permanently aligned

40 with the key slot 35 of the spindle. The second tumbler may have a hub 25 if found desirable. Both of the tumblers have pick up pins, on tumbler 21 a pin 23 projects from both faces, and on tumbler 24 a pin 70 26 is placed, facing the first tumbler. The action of tumblers and pins is well known, nevertheless it is well to describe their interaction. The pin 20 of cap 11 engages the pin 23 and this in turn acts against pin 26, thus through a series of right and left movements all the key slots 19, 22 and 27 will be brought opposite the key slot 35 of the spindle, ready to have the key 37 moved radially into them so as to permit the unlocking pin 47 to pass through the spindle into engagement with the pin 63 of the primary bolt 61.

45 The first thing to do in setting the lock so that the primary bolt 61 can be undone, is to bring all the key slots into line, then insert the pin 47 into the small hole of the cap until its rounded end 48 engages the curved end 38 of the key, at which time the key will be pushed endwise a slight amount to more easily let the pin pass under it. The notch 45 at the end of the key, may engage shoulder 9 and prevent the key projection 43 moving out of notch 19 and into too close engagement with the first tumbler 95 21. This endwise movement pushes the primary bolt a short distance in its course as shown in Fig. 1. On the withdrawal of the pin 47 and a pressure on the secondary bolt 51, the bolt 61 is again pushed into its full locking position by the spring 62 at which time the short pin 63, projecting from the body 59 of the bolt, pushes the key 37 to the end of the slot 35, until its curved end 38 engages the inside of the 105 cap 11 against the spindle recess 33 ready for a repeat operation.

50 The secondary bolt 51 has a locking end 52 that may enter an opening that needs to be locked, the instance in Fig. 1 shows a 110 steering wheel tube but this may be any other object. This bolt 51 slides in an opening 54 of the housing. It is cut away at 55 on one side to form shoulders. The locking end 52 is smaller in diameter than the 115 body of the bolt so as to pass through a coil spring 53 which pushes the secondary bolt into its unlocked position as soon as the primary bolt 61 has been moved endwise by the pin 47 so that the neck 60 will permit 120 the narrow slot 57 to engage it. When this occurs the upper edge of the head of the primary bolt 61 will engage the under flattened side 68 of the narrow slot where it 125 remains subject to the tension of the spring 62 until it is desired to lock the car, or whatever object to which the device is applied, by simply pressing on the end 58 of the bolt 51 to cause the end 52 to complete the locking operation. This permits the spring 130

62 to move the primary bolt toward the key and bring the head 61 into the larger slot 56, effectively holding the secondary bolt 51 against movement until such time as the 5 primary bolt is again pressed against the spring 62 by the unlocking key 37.

It will be noted that the actual unlocking is done by means of the small diameter pin 47 which has no notches, grooves or configurations of any kind whatever. This makes it impossible to pick the lock as the permanently enclosed key 37 fills the slot 35 of the spindle, completely hiding the tumblers so that they cannot be manipulated by bent 15 wires, etc. When the tumblers are dispersed the key cannot be moved from its obstructive into a permissive position until the proper combination has been executed.

Should it be desirable to utilize audible 20 clicks, instead of depending on the visual graduations 13, the expedient instanced in Fig. 6 may be employed. At any available part of the cap tube 15 a series of circumferential V-shaped notches 64 may be 25 cut. A "zero" or starting notch 67 may be made deeper so as to, in this or any other way, indicate the starting point for the cap 11. The audible or digital indications 30 are given by the spring pressed detent 65 which is suitably secured in a recess or groove 66 of the casing. This detent may be of very simple well-known construction comprising only a narrow flat spring with a V-shaped bend at its free end or a similar 35 V-shaped block 65 secured to such end, both of which are well understood expedients.

What I claim is:

1. In permutation locks, a suitable housing, a plurality of revolvable disks therein, 40 each disk having a central opening therethrough and a radial notch formed in the periphery of the opening, a slotted spindle within the housing passing through the openings, a rotatable dialed cap secured in the housing to enclose the spindle, a spring 45 pressed key permanently located in the slot of the spindle, means for actuating the disks through a movement of the cap to bring the internal notches of all the disks in line opposite the key, and means for moving the key radially into said notches and thereby 50 perform an unlocking operation by said means.

2. In permutation locks, a self-contained 55 housing, a spindle having an opening therethrough lengthwise thereof and a continuous radial slot connected with the opening, a notched key permanently located in the slot, and means external of the housing for selectively holding the key in a permissive or obtrusive position within the spindle opening.

3. In permutation locks, a cylindrical 60 housing having a large chamber therein, a smaller bore outlet from the chamber, a ro-

tatable cap closing the chamber, a stationary spindle within the cap and the bore, a radial slot throughout the length of the spindle, one or more permutable and interdependent tumblers within the chamber said tumblers 70 and cap having internal notches alignable with the slot in the spindle, means on the cap to actuate the tumblers, a spring pressed key within the slot adapted to keep a parallel passage through the spindle closed 75 until the series of notches are in alignment, and means externally admissible for moving the key radially into the notches while passing through the spindle slot in contact with the key.

4. In permutation locks, a plurality of interdependent permutable members enclosed in a suitable housing, means accessible from the exterior of the housing for actuating the members, a slotted spindle having a lengthwise opening located within the members, a permanently enclosed notched key within the spindle slot, and means for automatically moving the key radially into a changed 80 position in the slot and said opening through 85 a selective positional change of said members.

5. In permutation locks, a self contained housing, a radially movable notched key, a spindle provided with a continuous radially positioned slot for the key and having an opening lengthwise thereof in communication with said slot, and external means for selectively controlling the movement of the key at will to thereby change its position 90 with the spindle slot from an obstructive 95 to a permissive position in the opening.

6. In permutation locks, a casing, a cap therefor, a spindle therein, a lengthwise slot of the spindle, one or more members having internal notches rotatable on the spindle, a key permanently enclosed in the casing and adapted to normally keep said slot closed, means external of the casing for selectively actuating the members in sequential relation so as to permit a movement of the key to clear a part of the slot, and external means adapted to fill such cleared space and have free passage therethrough while the key is positioned to hold all the 105 members against movement until such external means is removed and the key is automatically withdrawn from engagement with the members and replaced within the 110 slot of the spindle.

7. In permutation locks, a self-contained housing, a plurality of permutation members in the housing, a spindle within said members, a lengthwise opening through the spindle, a radial continuous slot in the spindle communicating with the opening, a notched key slidably in the slot adapted to normally close the opening, and cooperating means between the key and the permutation members adapted to permissively clear 125 130

the spindle opening or obstruct the same as desired.

8. In permutation locks, a self-contained housing, a rotatable spindle placed within the housing and terminating exterior thereof, a permanently positioned key located in the spindle, a bolt adjacent the interior end of the spindle, external means for selectively

controlling the movement of the key to permit or obstruct the operation of the bolt ¹⁰ from the exterior of the spindle through a change in position of the key enclosed in the spindle.

In testimony whereof I affix my signature.

FRANK HORAK.
